UNITED STATES PATENT OFFICE.

FORBES C. WELSH AND WILLIAM H. GATES, OF WINDSOR, ONTARIO,
CANADA.

BRUSH.

SPECIFICATION forming part of Letters Patent No. 439,914, dated November 4, 1890.

Application filed March 8, 1890. Serial No. 343,186. (No model.)

To all whom it may concern:

Be it known that we, FORBES C. WELSH, a British subject, and WILLIAM H. GATES, a citizen of the United States, both residing at 5 Windsor, Ontario, Canada, have invented certain new and useful Improvements in Brushes; and we do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 This invention relates to brooms and brushes; and it consists in a certain construction and arrangement of parts, whereby the brush-head is connected to the handle thereof by flexible arms and in such manner that 20 the brush-head is adapted to oscillate, and may be secured at any angle, so that the bristles or strands of the brush-head will stand in a line with the handle or at right angles thereto as desired, and a further arrangement 25 of parts, whereby the brush-head may be bent to one side and rigidly secured in that position, all of which will be hereinafter more fully set forth, and the essential features of the device pointed out particularly in the 30 claims.

In the accompanying drawings, forming a part of the specification, Figure 1 is a side elevation of our improved brush, showing by dotted lines the shifted positions of the brush-head. Fig. 2 is an edge view of the brush, showing the flexible arms of the brush-head bent to one side carrying the brush-head out of line with the handle, and the means for securing the brush-head in such position, a 35 portion of the brush-head being broken away, showing a set-screw passing therethrough and engaging one of the flexible arms of the brush-head. Fig. 3 is a central vertical section through the brush-head and a portion of the 40 handle.

Referring to the letters of reference, A indicates the brush-head; B, the handle of the brush, and C and D the resilient arms that connect the brush-head to the handle.

45 The arms C D may be made of any suitable

material, spring metal, however, being preferred. The arm D is substantially U-shaped, and is provided with the hooked ends c c. Said arm passes freely through the opening e in the end of the handle B, and its hooked ends 55 are placed in holes formed in the brush-head A and secured therein by driving the pins s s through said brush-head, so that the hooked ends c will engage therewith. The plugs t t are then inserted in the holes in the brush-head, thus firmly anchoring the ends of the arms D therein, as shown in Fig. 3.

The arm C is loop-shaped, its ends being permanently secured in the end of the brush-handle, as shown at n in Fig. 3, and the circle or loop of said arm being adapted to lie freely within the circular groove v in the brush-head, and is held in place by the staples i, that are driven into the brush-head astride of said arm, whereby the head A is adapted 70 to oscillate, sliding upon the circular or looped portion of the arm C, that lies within the groove v in said head, as shown by dotted lines in Fig. 1, the arm D of said head sliding in the opening e through the end of the handle as 75 the head oscillates, and by means of the set-screw a, that passes through the end of the handle at right angles to the opening e, and engages with the arm D therein, the head A may be locked in any position. This oscillat- 80 ing feature of the brush-head is very important, for should it be desired to sweep or dust under an article of furniture the brush-head may be oscillated to either of the dotted positions of Fig. 1, in which position of the 85 brush-head the carpet under a bed, for instance, may be effectively swept, as the ends of the bristles or strands of the brush or broom are brought directly in contact therewith, as will be readily understood.

The coupling rod or link f (shown in Fig. 2) is provided at its lower end with the spring clasp or hook o and at its upper end with the eye o', said link being attached to the brush-handle by means of the screw-eye c', in which 95 it is adapted to slide up and down. The purpose of the link f is to secure the brush-head in a position at an angle to the line of the handle. To accomplish this, the link is drawn upward until the hook o thereof engages the

screw-eye c' . The brush-head is then sprung over, and the hook a'' therein engaged in the eye a' of the link, thereby retaining the brush-head in the position shown in Fig. 2, in which 5 position the brush is especially serviceable for cleaning walls and windows.

When the link f is unhooked from the brush-head, the resilient arms CD return said head to its normal position, and the link is secured by passing it down through the eye c' and entering the hook o in the eye c'' on the handle, whereby it is retained in place, as shown by dotted lines in Fig. 2.

Having thus fully set forth our invention, 15 what we claim as new, and desire to secure by Letters Patent, is—

1. In combination with the brush head and handle, the arm D , having its ends attached to the brush-head, its body slidingly coupled 20 to the handle, and the arm C , having its ends attached to the handle, its body slidingly coupled to the brush-head, substantially as specified.
2. In combination with the brush body and 25 handle, the flexible arms uniting said parts, the **U**-shaped arm having its ends secured to the brush-body, its curved portion passing

freely through the handle and having means to lock said arm to the handle, and the flexible arm C , secured to the handle and having its 30 curved portion slidingly coupled to the brush body, for the purposes specified.

3. In combination with the brush head and handle, the curved flexible arm $C D$, uniting said parts, the coupling-link slidingly attached to the handle at one end and its opposite end adapted to be engaged with the brush-head, substantially as specified. 35

4. In combination with the brush head and handle, the spring-metal arms coupling said parts, the **U**-shaped arm having a sliding engagement with the handle, the arm C , having a sliding engagement with the brush-head, the set-screw in the handle, and the spring-link having a sliding engagement with the handle 40 and a detachable engagement with the brush-head, substantially as set forth. 45

In testimony whereof we affix our signatures in presence of two witnesses.

FORBES C. WELSH.
WILLIAM H. GATES.
